(57) **CLAIM**

The ornamental design for a case for portable electronic communications device, as shown and described.

DESCRIPTION

FIG. 1 is an isometric front view showing the new design for a case for portable electronic communications device; FIG. 2 is an isometric back view showing the case for portable electronic communications device;

FIG. 3 is a front view showing the case for portable electronic communications device;

FIG. 4 is a left side view of the case for portable electronic communications device;

FIG. 5 is a right side view of the case for portable electronic communications device;

FIG. 6 is a top view of the case for portable electronic communications device;

FIG. 7 is a bottom view of the case for portable electronic communications device; and,

FIG. 8 is a back view of the case for portable electronic communications device.

The broken lines depict portions of the case for portable electronic communications device that form no part of the claimed design.
